UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

PLATE-CLAMPING MEANS FOR ROTARY CYLINDERS.

1,275,643.

Specification of Letters Patent. Patented Aug. 13, 1918.

Application filed May 3, 1915. Serial No. 25,525.

To all whom it may concern:

Be it known that I, HENRY F. BECHMAN, a citizen of the United States, residing at Battle Creek, in the county of Calhoun and State of Michigan, have invented certain new and useful Improvements in Plate-Clamping Means for Rotary Cylinders; and I hereby declare that the following is a full, clear, and exact description thereof, reference being had to the accompanying drawings, which form part of this specification.

This invention relates to the means for fastening stereotype plates on plate cylinders of rotary printing presses, and its object is to provide a novel major device for adjusting the several plate clamps that engage the ends of the same plate, so that such clamps may be operated simultaneously by the major device and may also be independently adjusted relative to said device so that the clamps will properly engage the plate when operated by the major device. In this manner time is saved in fastening the plates on, or removing them from, the plate cylinders.

The invention consists in the novel major clamp operating means which will be clearly understood from the accompanying drawings and the following description, and in the claims are summarized the essential features and combination of parts for which protection is desired.

In said drawings:

Figure 1 is an end elevation of one-half of an ordinary rotary printing press plate-cylinder showing my novel clamping devices in elevation.

Fig. 2 is a longitudinal sectional elevation on line 2—2, Fig. 1.

Fig. 3 is a view similar to Fig. 2 showing a slight modification.

Fig. 4 is a view similar to Fig. 2 showing another slight variation.

The plate cylinder 1 may be of ordinary construction, such as commonly used in the well known rotary printing presses, and adapted to carry two diametrically opposite semi-cylindric plates on its periphery, said plates being indicated at 2. The said cylin-

der is provided with the usual longitudinal grooves in which are ordinary plate clamps 3 which are mounted upon bolts 4 that have square headed ends as usual, so they can be turned by an ordinary wrench or clamp operating tool.

In the present invention the bolts 4 are extended through the arms of a yoke 6, which as shown has three arms with each of which a bolt 4 is rotatably engaged, but each bolt is confined against longitudinal movement relative to the yoke by suitable means, a collar 4^a being shown on the bolt outside the yoke, and jam and lock nuts 4^b, 4^c screwed on the bolt inside the yoke 6.

The yoke 6 is provided at the junction of the arm with a hub portion 6^a through which passes a bolt 5 which in the form shown in Fig. 2, is exteriorly threaded and tapped into a correspondingly threaded socket 1^c in the end of the cylinder, and this bolt 5 is provided at the outer side of the yoke with a collar 5^a and at the inner side of the yoke with adjusting and jam nuts 5^b, 5^c, which prevent longitudinal movement of the bolt 5 relative to the yoke without preventing rotation of the bolt. The bolt has a squared outer end 5^d which may be engaged by the usual wrench or tool to turn the bolt. The bolt 5 is arranged at about the hub or center of pressure upon the yoke, so that all the clamps will have a practically equal pressure exerted thereon and the yoke will not yield unequally under strains, the clamping bolt 5 being nearer the axis of the cylinder than any of the clamp bolts 4.

By turning the bolt 5 the yoke 6 will be moved toward or from the adjacent end of the cylinder 1 and will correspondingly move the several bolts 4 and clamps 3 inward or outward; and thus by manipulating one bolt 5 all the bolts 4 attached to said yoke and the clamps 3 on said bolts 4 can be simultaneously moved inward or outward. Each clamp 3 may be adjusted independently of the yoke by turning the related bolt 4, and said bolt can be locked when adjusted by tightening the nuts 4^b, 4^c. Each clamp 3 when adjusted to proper plate-engaging po-

sition on its bolt 4 can be locked thereon by means of a jam-nut 3^a.

In preparing the device for operation the bolt 5 should be turned so as to move the yoke slightly away from the end of the cylinder; then a plate 2 is placed on the cylinder 1 and the clamps 3 adjusted thereagainst by turning the related bolts 4 independently, the bolts 4 are then locked against longitudinal movement by the nuts 4^b, 4^c, and each clamp is locked on its bolt by the nuts 3^a. Then by turning the bolt 5 the yoke 6 can be moved to or from the end of the cylinder and all the connected clamps will be simultaneously forced inward against the plate; or can be simultaneously withdrawn to release the plate. Thus plates can be fastened upon or removed from the cylinder by merely adjusting the yoke, which is a great saving of time as compared with independently operating or manipulating each of the clamp bolts.

In the construction shown in Fig. 3 instead of tapping bolt 5 directly into the cylinder this bolt is tapped into an internally threaded sleeve 7 which can be pressed into a suitable socket 1^a in the cylinder. The yoke 6 may be slidably mounted upon the outer end of this sleeve and the bolt 5 may have a collar 5^e, arranged within the bore in the yoke and adapted to engage a flange 6^e at the outer end of this bore, and locking and jam nuts 5^f are screwed on the end of the bolt 5 outside of the yoke, so that the bolt 5 is free to turn within the yoke but the yoke is caused to follow the endwise movements of the bolt.

In Fig. 4, in place of the bolt 5, I show a sleeve bolt 8 which is externally threaded to engage an internal thread within the bore of the yoke, and it is also internally threaded to engage the threaded outer end of a stud 9 which is forced into the socket 1^e in the cylinder. The threads on this sleeve bolt 8 are so formed that when the sleeve is turned so as to move it on stud 9 its outer threads also cause an additional and accelerated movement of the yoke in the same direction; thus reducing the number of rotations required to move the yoke a given distance in either direction. In this construction when the bolt 8 is turned it is also moved endwise by reason of the threads 8^a and 8^b and the yoke is moved with the sleeve bolt.

55 In each construction shown the major clamping bolt is located at the point of greatest pressure on the yoke and nearer the axis of the cylinder than any of the individual clamps.

60 The invention is readily applicable to ordinary plate cylinders already in use, and does not require any material change in the structure of said cylinders, and in each instance it will be seen that while the plate 65 clamps are independently adjustable, they

can when once adjusted all be simultaneously shifted so as to simultaneously engage or release a plate.

What I claim is:

1. In combination with a plate cylinder 70 having a plurality of plate clamps; of a yoke adjustably attached to the end of the cylinder and having outwardly projecting radiating arms; clamp adjusting screws engaged with the extremities of said arms; 75 and a threaded member extending axially parallel with the cylinder and rotatably connected with said yoke at the junction of the arms thereof and nearer the axis of the cylinder than any of the clamps; there being 80 a threaded engagement between the cylinder and the member, whereby by turning said threaded member the yoke may be adjusted to or from the end of the cylinder to simultaneously shift the clamps. 85

2. In combination with a cylinder, a series of plate clamps, and screws for independently adjusting said clamps; of a yoke at one end of the cylinder having a plurality of outwardly projecting radiating arms; a 90 member lying axially parallel with said cylinder and rotatably engaged with said yoke at the junction of said arms, and nearer the axis of the cylinder than any of the clamps; there being a threaded engagement between 95 the cylinder and said member whereby upon rotating said member the yoke is moved to or from the end of the cylinder; said clamp screws being rotatably engaged with the yoke arms at points farther removed from 100 the axis of the cylinder than said member, and movable with said yoke to shift the clamps simultaneously.

3. In combination with a cylinder, a yoke at one end thereof, a bolt rotatably engaged 105 with said yoke there being a threaded engagement between the bolt and the cylinder whereby upon rotating said bolt the yoke is moved to or from the cylinder; with a series of plate clamps; bolts for independently adjusting said clamps, said bolts being 110 rotatably engaged with said yoke and movable therewith to shift the clamps simultaneously; means for locking the clamp bolts 115 properly adjusted; and means for locking each clamp on its bolt.

4. In combination a plate cylinder, a stud attached to its end, a rotatable bolt having a threaded engagement with said stud, a 120 yoke rotatably engaged with said bolt so as to be moved thereby to or from the cylinder, a set of plate clamps, and independently rotatable bolts engaged with said yoke and engaging the clamps; whereby said clamps 125 may be adjusted independently of the yoke, and said clamps may be simultaneously adjusted with the yoke by turning said rotatable bolt.

5. In combination with a plate cylinder 130

having a threaded member at its end; plate clamps, and plate clamp adjusting bolts; of a yoke connected with the clamp adjusting bolts, and a sleeve bolt having a threaded engagement with said yoke and having an internally threaded portion engaging the threaded member attached to the cylinder.

In testimony that I claim the foregoing as my own, I affix my signature in presence of two witnesses.

HENRY F. BECHMAN.
